CLAIM

The ornamental design for a heat recovery air exchanger, as shown and described.

DESCRIPTION

FIG. 1 is a front perspective view of the heat recovery air exchanger;

FIG. 2 is a front view of the heat recovery air exchanger;
FIG. 3 is a right side view of the heat recovery air exchanger;
and,

FIG. 4 is a top view of the heat recovery air exchanger.
In the drawings, the broken lines depict unclaimed subject matter only and form no part of the claimed design.
